UNITED STATES PATENT OFFICE

171,024

PLAQUE

Camiel A. Blondeel, Chicago, Ill.

Application April 29, 1953, Serial No. 24,760

Term of patent 7 years

(Cl. D29—23)

To all whom it may concern:

Be it known that I, Camiel A. Blondeel, a citizen of the United States, residing at Chicago, in the county of Cook and State of Illinois, have invented a new, original, and ornamental Design for Plaque, of which the following is a specification, reference being had to the accompanying drawings forming a part thereof, in which:

Figure 1 is a top plan view of a plaque, showing my new design, the portion shown in full lines being repeated throughout the periphery thereof as indicated by the broken lines;

Fig. 2 is a side elevational view thereof taken partially in section along the line 2—2 of Fig. 1;

Fig. 3 is a fragmentary sectional view thereof taken along the lines 3—3 of Fig. 1; and

Fig. 4 is a fragmentary sectional view thereof taken along the line 4—4 of Fig. 1.

I claim:

The ornamental design for a plaque, substantially as shown and described.

CAMIEL A. BLONDEEL.
